UNITED STATES PATENT OFFICE.

HANS HONIGMANN, OF DULUTH, MINNESOTA.

SHEET-REGISTERING DEVICE FOR PLATEN PRINTING-PRESSES.

1,147,506.

Specification of Letters Patent.

Patented July 20, 1915.

Application filed April 9, 1914. Serial No. 830,729.

To all whom it may concern:

Be it known that I, HANS HONIGMANN, a citizen of the United States, residing at Duluth, in the county of St. Louis and State 5 of Minnesota, have invented certain new and useful Improvements in Sheet-Registering Devices for Platen Printing-Presses, of which the following is a specification, reference being had therein to the accompanying drawing.

My invention relates to improvements in sheet registering devices for platen printing presses.

The object of my invention is to provide 15 a device of this character adapted to be used in connection with automatic sheet feeders for platen printing presses such as shown in my Patents 970,822 dated September 20, 1910, and 1,074,720 dated October 7, 1913 20 which will insure of registering the vertical position of the sheet on the platen and, at the same time, to insure true alinement, vertically of the sheets to be printed, on the platen.

25 Another object of my invention is to provide a simple, cheap and effective device of this character which can be readily applied to the feeders of the character heretofore described and capable of ready adjustment 30 to suit the various requirements of such a device.

In the accompanying drawings: Figure 1 35 is a side elevation diagrammatically shown of a reciprocating feeder showing my device applied thereto. Fig. 2 is an enlarged perspective view of the outer sheet registering arm.

Referring now to the drawings in which like reference numerals designate similar 40 parts, 1 represents the ordinary pivotally mounted platen commonly used on platen printing presses and carries the conveyer belt 2 which is adapted to receive the printed sheets from the platen of the press and 45 conveying them rearwardly to be stacked as is readily understood by those skilled in the art.

The frame 3 of the feeding mechanism 50 carries a longitudinally arranged track or groove 4, in which the reciprocating carriage 5 operates. The carriage 5 has pivotally connected thereto the reciprocating feeding arms 6 which extend forwardly and are adapted to feed the sheets of paper to and 55 from the press as is fully illustrated in the patents above referred to and need no fur-

ther description as the specific form of these feed arms forms no part of this invention.

While I have shown but one reciprocating feeding arm, it will be understood that 60 there are usually a plurality of these arms and the arm shown in the drawings is the central one, it being the one working in conjunction with my present device.

The reciprocating carriage 5 is operated 65 backward and forward by means of the track 7 mounted thereon and which is in turn actuated by a gear driven by a connection with the press and imparting a backward and forward motion to the track to 70 cause the feeding arms to reciprocate, to feed the sheets of paper to and from the platen of the press.

The main shaft 8 of the feeding mechanism is provided with two cams 9 and 10 75 and carried by the feeding mechanism frame. Mounted within the feeding mechanism frame 3 forward of the shaft 8 is a fixed shaft 11 upon which is rigidly mounted a casting having the two rearwardly extending arms 12 and 13. The arm 12 extends slightly upwardly and terminates at a point close to the shaft 8 and pivotally mounted upon the extreme end thereof is a crank 14 having the short arm 15 upon the 85 end of which is mounted the roller 16 which bears against the cam 9 upon the shaft 8. The arm 13 extends in a downwardly direction from the shaft 11 and has pivotally connected at its outer end 13' an arm 17 90 which extends upwardly and carries a roller 18, which is mounted upon its extreme upper end and said roller bears against the cam 10. Pivotally connected to the outer end of the arm 17 is a horizontally arranged 95 arm 19. Connected to the end 13' of the arm 13 is an outwardly and slightly upwardly inclined arm 20 to the outer end of which is connected a spring 21 the opposite end of this spring being connected to the arm 17 100 intermediate its end which will maintain a constant pressure of the roller 18 carried thereby upon the cam 10. This spring also causes a pressure through the arms 12 and 13 to cause the roller 16 to bear upon the 105 cam 9. It will also be seen that the arms 14 and 19 of my device will be actuated or moved forward by the rotation of the shaft 8 and the engagement of the cams 9 and 10 with the rollers 16 and 18 carried by the arm 110 17 and the arm 15, respectively.

The arms 19 and 14 as shown in Figs. 1

and 2 of the drawings extend forwardly and are of a hollow form for the greater part of their length and have their outer ends screw-threaded taperingly as indicated at 19' and 14'. These threaded portions 19' and 14' are split for the purpose hereinafter more fully described. The rods 22 and 23 extend within the hollow threaded ends of the arms 19 and 14 and whereby 5 they are adjustably held within the same. Screwed upon the threaded portions 19' and 14' of the rod 19 and 14 are lock nuts 24 and 25 which are adapted to contract the split threaded portions 19' and 14' when screwed upwardly thereupon and thus rigidly clamp the rods 22 and 23 in their adjusted position. The rod 23 is provided with a fixed collar 26, and slidably mounted upon the rod 23 10 beyond the collar 26 is a collar 27. Surrounding the rod 23 between the collars 26 and 27 is a coil spring 28 which normally holds the slidable collar 27 in its outward position. In order to limit the outward movement of the slidable collar 27, the outer end of the rod 23 is screw-threaded at 23' 15 and upon which is mounted a nut 29. By this nut 29 it will be seen that the outward movement of the sleeve 27 is varied for a purpose hereinafter more fully described. 20 Pivoted to the slidable sleeve 27 is a downwardly extending arm 30 which is pivotally connected at 32' to a lever arm 32. The opposite end of the lever arm 32 is pivotally connected to the outer end of the rod 22. 25 The lower extremity of the arm 30 is provided with a hook 33 and a similar hook 34 is provided upon the lower end of the side arm 35 rigidly attached to the arm 30. These two hooks form means of retarding a 30 sheet from returning upon the feeder arm 6 when the latter begins to return. Above the hooks is a curved leaf 36 and a roller 31 carried by the lower end of the arm 30 and also assist in holding the sheet in its proper 35 alignment upon the platen of the press.

In operation of the above described device, it will be understood that the cams 9 and 10 are so adjusted that the lever arms 14 and 19 will maintain the arm 30 in the above described position while the reciprocating feeder arms 6 are returning to their normal position after having placed the sheet of paper upon the platen. By the rotating motion of the shaft 8 and the peculiar shape 50 of the cams 9 and 10, after the arm 6 has returned and the sheet is in its proper place upon the platen of the press, the arm 30 will be withdrawn and raised from the platen to allow the printing of the sheet. This is accomplished as follows: The roller 18 will be forced downwardly by the motion of the cam 9 and will thereby raise the arm 14 and thus the lever arm 30 through its connection therewith will be also raised. The cam 10 will then force the roller 18 forward, thus

forcing the arm 19 forward and the rod 23 and their attached parts are likewise forced forward and the arm 30 will be drawn backward by the action of the fulcrum formed at the connection of the arm 30 with the lever 32. This arm 30 is withdrawn from above the platen of the press to allow the same to move forward for placing the sheet thereon as is more fully understood by those skilled in the art. 75

Having thus fully described my invention what I claim and desire to secure by Letters Patent is:

1. The combination with a sheet feeding device for a platen printing press, reciprocating sheet feeding members carried by the feeder, an oscillating arm carried by the feeder and adapted to register the horizontal position of the sheet on the feeder arm and on the platen of the press. 80

2. The combination with a printing press of a sheet feeding mechanism thereon, reciprocating sheet feeding arms carried by the feeder and adapted to feed the sheets to and from the press, and an oscillating arm above the sheet feeding members, and adapted to register the horizontal position of the sheets on the feeder arm and on the platen of the press. 85

3. The combination with a sheet feeding device, for printing presses, having reciprocating sheet feeding arms adapted to feed the sheets of paper to and from the platen of a printing press, cams carried by the sheet feeding device, an oscillating arm 100 adapted to register the horizontal position of the sheets on the press and means operated by the cams for oscillating said arm substantially as shown and described. 90

4. The combination with a sheet feeding device for platen printing presses, having reciprocating sheet feeding arms adapted to feed the sheets of paper to and from the platen of the press, continuously rotating cams carried by the sheet feeding device, an oscillating arm adapted to register the horizontal position of the sheets on the press, and means operated by the cams for oscillating the said arm. 95

5. The combination with a sheet feeding device for printing presses, having reciprocating sheet feeding arms adapted to feed the sheets of paper to and from the platen of the press, continuously rotating cams carried by the feeding device, cranks operated by the said cams, arms carried by the cranks, a vertically disposed sheet registering arm, and supported by the arms of the cranks for registering the horizontal position of the sheets on the reciprocating feeder arms, and on the platen of the press, and means for rotating said cams. 105

6. The combination with a feeding device for platen printing presses having reciprocating feeder arms adapted to feed the 110

sheets to and from the platen of the press, two continuously rotating cams carried by the feeding device, an arm mounted upon the feeding device, a crank intermediately pivoted to the arm and having one end engaging one of the cams, a vertically disposed sheet registering arm carried by the opposite end of the crank below its upper end, a second crank pivoted at one end to the lower end of the arm and adapted to be engaged by the second cam and having a horizontal portion extending to and connected to the upper end of the vertically disposed registering arm and sheet engaging fingers carried by the lower end of the feeder arms substantially as shown and described.

7. The combination with a sheet feeding device for platen printing presses having reciprocating feeder arms adapted to feed the sheets to and from the platen of the press, two continuously rotating cams carried by the feeding device, a crank arm mounted upon the feeding device and adapted to oscillate a second crank arm pivoted to one end of the first crank arm intermediate its end, one end of said second crank arm engaging one of the cams, the opposite end extending horizontally, a link 25 adjustably connected to the end of said horizontal portion of the second crank arm, a sheet registering arm having the link connected thereto below its upper end, a crank 30 connected to the lower end of the first crank arm and adapted to engage the second cam intermediate its ends, said crank having a horizontal portion, a sleeve horizontally adjustable thereon, and the upper end of the sheet registering arm pivotally connected to 35 said sleeve, and sheet engaging members carried by the lower end of said sheet registering arm, whereby the sheet is registered in its horizontal position upon the sheet feeding arms and on the platen of the press 40 substantially as shown and described.

8. The combination with a feeder for a platen printing press having reciprocating feeder arms adapted to feed the sheets of paper to and from the platen of the press, 45 of an oscillating arm adapted to register the vertical position of the sheets on the feeder arm and means for oscillating said arm, whereby the sheets are centered upon the platen of the press substantially as shown and described.

9. The combination with a sheet feeding device for a platen printing press having reciprocating feeder arms adapted to feed the sheets of paper to and from the platen

of the press, an oscillating arm carried by 60 the feeding device and having means at its lower end for engaging the sheet on the reciprocating feeding arms, and having a second sheet engaging member rigidly carried thereby and means carried by the feeding 65 device for oscillating said arm, whereby the same is adapted to register the horizontal position of the sheets on the platen of the press substantially as shown and described.

10. The combination with a feeding device for a platen printing press, having reciprocating feeder arms adapted to feed the sheets of paper to and from the platen of the press, an oscillating arm carried by the feeder and having a sheet engaging member 70 at its lower end, a roller carried by the arm above the sheet engaging member, and an upward and outward curved lug carried by the arm opposite the roller and means carried by the feeding device for oscillating the 75 arm for registering the horizontal position of the sheets on the platen of the press substantially as shown and described.

11. The combination with a feeding device for a platen printing press having reciprocating feeding arms adapted to feed the sheets of paper to and from the press, 80 two rotating cams carried by the feeder, an arm carried by the feeder and adapted to oscillate a crank intermediately pivoted to 85 the upper end of the arm, and having one end engaging with one of the cams and its opposite end extending horizontally forward, a second crank pivotally connected to the lower end of the arm and adapted to 90 engage the other cam intermediate its end, and having a horizontal forward extending portion, a rigid arm carried by the lower end of the arm, a spring connected to the said arm and to the second crank, a spring 100 pressed sleeve horizontally movable upon the horizontal portion of the second crank, a centering arm pivotally connected to said sleeve, a link connected to the centering arm and having its inner end pivotally connected to the outer end of the first crank, sheet 105 engaging members carried by the lower end of the arm for registering the horizontal position of the sheets on the platen of the press and means for operating 110 the cams substantially as shown and described.

In testimony whereof I hereunto affix my signature in the presence of two witnesses.

HANS HONIGMANN.
